C. A. VANDERVELL & COMPANY LIMITED, OF ACTON VALE, ENGLAND.

IGNITION SYSTEM FOR INTERNAL-COMBUSTION ENGINES.

1,351,396.

Specification of Letters Patent.

Patented Aug. 31, 1920.

Application filed February 6, 1919. Serial No. 275,360.

To all whom it may concern:

Be it known that I, ALBERT HENRY MIDGLEY, a subject of the King of Great Britain and Ireland, and residing at Warple 5 Way, Acton Vale, in the county of Middlesex, England, have invented certain new and useful Improvements in and Relating to Ignition Systems for Internal-Combustion Engines, of which the following is a specification.

This invention relates to an improved ignition system for internal combustion engines of the kind in which a dynamo arranged in parallel with a battery of accumulators is connected to the ignition coil, or coils, the battery being more particularly intended to supply current to the latter at starting and the dynamo to supply the current to such coil or coils after the engine has 20 started to rotate under its own power.

The main object of the invention is to provide improved means of connections so as to reduce the amount of wiring and thereby the weight of the whole system, which is of 25 special importance in connection with aircraft, another object being to insure the working of the ignition circuit when one or more of the connections are broken.

According to the present invention the 30 ignition coil with its circuit breaker, the dynamo and the battery are star and delta connected, that is to say they are connected at one end to a common point, while their other ends are interconnected as in the well known 35 delta connection, preferably through earth connections, and the part of the star connection which includes the battery also includes a switch which is interposed between the battery and a connecting wire coming from 40 the common point of the star connection and is adapted in one position to connect the battery to the dynamo and ignition coil and in the other position to disconnect it therefrom and short-circuit both the dynamo and the 45 ignition coil.

With this arrangement the size of the wire between the switch and the ignition unit is small as it only carries the difference between the ignition current and the dynamo 50 current.

The invention also consists in arranging that the short-circuiting connection effected by the switch shall also effect the short-circuit of the shunt winding of the dynamo 55 when the automatic cut-out is open. In or-

der to effect this, the automatic cut-out is inserted in the connection between the one brush of the dynamo and the common point of the star connection, while one end of the shunt winding is connected to the said common point and its other end to the same point as the other brush of the dynamo, preferably the earth.

Referring to the accompanying drawing which illustrates the invention diagrammatically and by way of example, a^1, a^2 are two distributors associated with two banks of cylinders, b^1, c^1 the primary and secondary coil of the ignition coil and d^1, e^1 the cam and earthed make and break of the circuit breaker associated with one bank of cylinders, and b^2, c^2 the primary and secondary coil of the ignition coil and d^2, e^2 the cam and earthed make and break of the circuit breaker associated with the other bank of cylinders.

The dynamo f , one brush g of which is earthed while its other brush g is connected to the ignition system by a connecting wire h , is provided with a shunt winding i , one end of which is earthed while its other end is connected to the point of connection j between the dynamo and the ignition system, the automatic cut-out k being inserted between the brush g^2 and the point of connection j .

The connecting wire h between the dynamo and the ignition coils is connected to the earthed battery l by means of a two-way switch m , which in one position connects 90 both the dynamo and the ignition coils to the battery, and in the other position disconnects the battery and short-circuits both the dynamo and the ignition coils through earth.

Each of the ignition coils is preferably provided with a trembler n^1, n^2 respectively, which are controlled by the closing of an earthed switch o and are operative when the corresponding make and breaks e^1, e^2 are 95 open.

The ignition coils, automatic cut-out, distributors and dynamo are all mounted together in such a manner as to form a compact unit.

What I claim is:

1. An ignition system for internal combustion engines comprising in the combination of an ignition coil and circuit breaker, with a battery for supplying current to 110

said ignition coil at starting and with a dynamo for supplying current to the ignition coil after the engine has been started, an electrical star connection between the ignition coil with its circuit breaker, the dynamo and the battery and an electrical delta connection between the free ends of such star connection, the part of the star connection which includes the battery also comprising a connecting wire between the common point of the star connection and the battery, and a switch between the connecting wire and the battery, said switch having a movable contact arm and two stationary contacts, the movable contact arm being connected to the said connecting wire, and one of the stationary contacts being connected to the battery, while the second stationary contact of the switch is so connected as to be capable of short-circuiting both the dynamo and the ignition coil with its circuit breaker when the contact arm is in contact therewith, as and for the purpose set forth.

2. An ignition system for internal combustion engines comprising in the combination of an ignition coil and circuit breaker with a battery for supplying current to said ignition coil at starting and with a dynamo for supplying current to the ignition coil after the engine has been started, an electrical star connection between the ignition coil

with its circuit breaker, the dynamo and the battery, the free ends of such star connection being earthed and the part of the star connection which includes the battery 35 also comprising a connecting wire between the common point of the star connection and the battery, and a switch between the connecting wire and the battery, said switch having a movable contact arm and 40 two stationary contacts, the movable contact arm being connected to the said connecting wire, and one of the stationary contacts being connected to the battery, while the second stationary contact of the switch is 45 connected to earth, as and for the purpose set forth.

3. An ignition system for internal combustion engines as claimed in claim 2, the dynamo of which has a shunt excitation 50 winding connected at the one end to the common point of the star connection and at the other end to earth, and an armature connected at one end to earth and at the other end to an automatic cut-out which is 55 connected to the common point of the electric star connection, as and for the purpose set forth.

In testimony whereof I have signed my name to this specification.

ALBERT HENRY MIDGLEY.
